UNITED STATES PATENT OFFICE.

ARTHUR P. STRONG, OF CHICAGO, ILLINOIS, ASSIGNOR TO GREEN ENGINEERING COMPANY, OF EAST CHICAGO, INDIANA, A CORPORATION OF ILLINOIS.

ASH-CONVEYING SYSTEM.

1,243,893.

Specification of Letters Patent. Patented Oct. 23, 1917.

Application filed March 6, 1917. Serial No. 152,633.

To all whom it may concern:

Be it known that I, ARTHUR P. STRONG, a citizen of the United States, residing at Chicago, in the county of Cook and State of Illinois, have invented new and useful Improvements in Ash-Conveying Systems, of which the following is a specification.

This invention relates to improvements in conveying systems for ashes and like abrasive material, and more particularly to the means for impelling the material through the pipe line or conduit.

A particular type of conveying system embodying the features of this invention is known as the steam jet type, wherein steam at a high velocity is introduced into conduits through nozzles in the form of jets, thereby creating suction or partial vacuum within the conduit to advance the material therethrough.

As ordinarily constructed, systems of this type embrace a horizontal conduit located adjacent to the furnace, there being provided in the conduit one or more intake fittings provided with upwardly facing openings, normally closed by a suitable plug or other closure, said plugs being removed and the ashes introduced into the conduit through said intake openings. The conduit so provided with intake fittings communicates with a suitable disposal tank or receptacle into which the ashes are discharged. The steam nozzles are preferably mounted in especially designed fittings, located at one or more predetermined points along the horizontal conduit and adjacent to or intermediate the intake fittings.

Persons familiar with the properties of steam are well aware that steam under pressure is discharged from a nozzle or through a small orifice at a high velocity, which decreases as the steam expands—that is, there exists an inverse relation between the volume and velocity of the steam jet, dependent upon the initial pressure size of the orifice, as well as other factors. The discharge of the steam at the high velocity along the conduit and its expansive property has the effect of carrying with it the air and material behind it, thus creating the suction or partial vacuum in the conduit, whereby the motive or impelling power of the system is produced. Inasmuch as the steam is confined in a passage or conduit of uniform diameter or capacity, and the volume of ma-

terial carried thereby is variable, depending on the amount of ash discharged into the conduit at a given instant, a condition arises within the conduit which will be understood from the following. At a point some distance beyond the nozzle or point of discharge, the velocity of the steam is reduced to substantially the velocity of the material, and hence its power or propulsion expended. The volume of the steam, however, has increased with the decrease of velocity, and, as a result, pressure is created within the conduit which cannot be relieved or reduced, by condensation or by discharge from the outlet end of the conduit, owing to the size of the conduit and the comparatively large volume of steam discharged into it. It follows, therefore, that this pressure, if not relieved, tends to retard the movement through the conduit, and creates what is commonly known as back pressure, a condition which affects and reduces the efficiency of the system to a considerable degree. In order, therefore, to eliminate this disadvantageous condition of back pressure, it is the purpose of this invention to provide, at predetermined points in the conduit, auxiliary means whereby the back pressure can be relieved, by the use of relief pipes arranged as hereinafter fully described.

A preferable construction for accomplishing the purposes above set forth is herein-after fully described and illustrated in the accompanying drawings, wherein—

Figure 1 is a view in elevation of the principal portions of a conveying system, showing the relation of a relief pipe and parts thereof to the elements of the system;

Fig. 2 is an enlarged view of a special fitting used in connection with a relief pipe;

Fig. 3 is a cross-sectional view of the relief pipe fitting, taken on line 3—3 of Fig. 2;

Fig. 4 is a view in longitudinal section of a straight line nozzle fitting; and

Fig. 5 is a cross-sectional view of the nozzle fitting, taken on line 5—5 of Fig. 4.

As illustrated in the drawings, a horizontal conduit 10, preferably comprising metal pipe sections joined end to end by the usual flanged connections, communicates at its discharge end with a suitable disposal tank, through the medium of other conduits, such as a vertical riser 11. At several points along the conduit 10 are located a plurality

2
of intake fittings 12, said fittings being of any suitable construction, embracing an upwardly opening, funnel shaped passage communicating with the interior of the conduit, 5 there being also provided a suitable plug or closure for closing the intake opening when the same is not being used.

In addition to the intake fittings 12, the horizontal conduit 10 is further provided 10 with one or more so-called steam jet fittings 13, preferably located adjacent one or more of the intake fittings and preferably beyond the same in the direction of flow of the material. These steam jet fittings (Figs. 4 15 and 5) have the form of short pipe sections or casings 14, each provided about its circumference with a plurality of steam nozzles 15, rigidly mounted in nozzle casings 16, 16 integral with the fitting and inclined 20 at an angle to the axis of the fitting, so as to position the nozzles in such a manner as to direct the steam jets axially of the fitting so near as possible and in the direction of flow of the material. These fittings, further 25 more, are provided with a hand-hole 17, normally covered by a hand-hole plate 18, adapted to be removed when adjustment or renewal of the nozzles is necessary.

Located beyond the steam jet fitting 13, 30 and at a distance determined by conditions of steam pressure available, the diameter of the conduit, etc., is a fitting 19 (Figs. 1, 2, and 3), comprising in general a comparatively short straight pipe section 20 provided intermediate its ends with an upwardly extending and rearwardly inclined branch pipe or connection 21, the axis of said branch being preferably inclined at an angle of 45° to the axis of the straight section 20 and in a direction toward the steam jet fitting 13 with which the branch fitting is associated.

As a preferable construction, the branch fitting is provided along the bottom wall of 45 the straight portion 20 with a wear section 22, extending from a point immediately below the opening of the branch pipe 21 substantially to the end of the straight section distant from said branch. The wear section 50 is constructed of a hard metal adapted to resist the abrasive action of the material, and forms the surface of said straight portion below the center-line thereof. The wear section 22 is preferably removable, 55 there being provided a cover plate 23 extending over an opening below the wear section and removably secured to the pipe section by means of the usual arrangement of lugs, as at 24. Extending through the 60 cover plate 23 and through the sides of the wall of the pipe section, are conveniently positioned set screws 25, adapted to bear against the wear section and to hold the same in position. The purpose of locating 65 the wear section at this particular point in

the pipe line will be understood from the description of the function of the particular fitting of which it forms a part. For the purpose of permitting access to the wear section without removing the cover plate 23, 70 there is provided in the top wall of the straight portion 20 of the fitting 19, a hand-hole 26, normally closed by a cover plate 27 held in position by means of a locking bar 28 connected thereto at its center-point by 75 means of a bolt 29 and by means of locking shoulders 30 cast integral with the straight pipe section 20 adjacent the ends of the locking bar, the cover being released by loosening of the bolt 29 and rotating the 80 locking bar from engagement with the shoulders 30.

Communicating with the rearwardly inclined branch connection 21 of the fitting 19, 85 is a pipe 31, the same comprising a short curved section terminating at its upper end in a vertical direction. The lower end of the curved pipe 31 is joined to the branch connection 21 by the usual flanged connections, and at its upper end is similarly 90 joined to and communicates with an enlarged pipe section or hollow drum 32, the same comprising a vertically arranged, cylindric receptacle provided with a downwardly tapering or conical lower portion 33 95 terminating in an opening of the same diameter as the pipe section 31 below. Above the drum 32 is a vertical pipe 34 of a diameter smaller than the drum 32 and of the same diameter as the branch connection 21 100 and the curved pipe section 31. The vertical pipe 34 extends upwardly to any desired height, as for instance through the roof of the boiler room, and terminates in or is open to the atmosphere. At the top of the 105 vertical pipe 34 is mounted a check-valve or damper, preferably consisting of a circular flanged plate 35, pivotally mounted adjacent the edge of the end opening of said pipe and adapted to cover the opening at the 110 end of the pipe, and a counter-weight 36, mounted upon an arm 37 integral with the plate, extending outwardly beyond the point of pivotal connection. The check-valve, through the medium of the counter-weight 115 36, which is adjustable along the arm 37, is adapted to automatically open and close the end of the relief pipe, by the variation of pressure within the pipe; thus, when the pressure within said pipe approaches or 120 falls below the pressure of the surrounding atmosphere, the valve will close, thereby preventing a backward flow of air or "down draft" in the relief pipe. The valve, however, is so adjusted that it remains open under proper operating conditions, and hence serves chiefly in a precautionary capacity.

Referring now to the function and arrangement of the relief pipes, let it be assumed that the steam jets are in operation 130

nd the system is in proper operating condition to handle a quantity of ash. Upon opening one of the intake fittings and introducing a quantity of ash therein, the ash 5 is moved forwardly through the medium of the suction created in the conduit by the steam jets located beyond the intake fitting, the ash passing through the steam jet fitting, where it comes in contact with the 10 steam jets and is picked up thereby and moved forwardly at a great velocity. As the ashes and steam move beyond the steam jet fitting, the steam expands rapidly until a point is reached where the expansion of 15 the steam is so great as to create excessive pressure within the conduit and to create a back pressure therein, which has a tendency to oppose the flow of steam, air, and ash in a forwardly direction and to thereby reduce 20 the functioning of the system to a marked degree. It is at the point of maximum pressure within the conduit that the branch fitting 19 and the relief pipe communicating therewith are located. The purpose of the 25 relief pipe communicating with the conduit through the medium of the branch connection 19 is to afford means for relieving this excessive pressure, the relief pipe conducting a portion of the air and steam from the 30 conduit and discharging it into the atmosphere, thereby eliminating the back pressure.

The purpose of providing a rearwardly inclined or sloping branch connection is to 35 prevent, so far as possible, the passage of ash upwardly through the relief pipe, it being obvious that the material will be carried beyond the opening of the branch connection owing to its inertia, whereas the 40 steam and air are capable of being diverted in a backward direction and carried upwardly through the relief pipe. It is possible, however, that a certain amount of fine particles of ash will escape through the 45 branch connection and be carried upwardly through the relief pipe. The presence of the drum 32, used for the purpose of separating the ash particles from the air, prevents them from being carried upwardly therebeyond, 50 inasmuch as its increased volume affects a reduction of the velocity of the air therethrough to such an extent as to cause the particles of ash to lose their momentum and to drop by gravity to the bottom of the 55 drum, the sloping walls at the bottom thereof directing the ash into the pipe section 31, whereupon the same will gradually find its way back to the conduit and be carried forward with the main body of the material.

60 It is apparent that, by reason of the presence of the relief pipe, there occurs in the branch fitting 19 and immediately beyond the opening of the branch connection 21 a sudden decrease in the pressure and likewise 65 a sudden decrease in the velocity of the

material. For this reason a quantity of the ash will drop by gravity to the bottom of the pipe and be carried along in contact therewith until the stream and air have regained a velocity sufficient to pick up the 70 ash and hold the same in suspension. The presence of the wear section at the bottom of the branch fitting thus eliminates the wearing effect of the ashes upon the bottom wall of the fitting occasioned by the relief 75 pipe and for the reasons pointed out.

It is obvious from the description of the construction herein illustrated, that the advantages attending its use are directed toward securing greater efficiency in operation, by the eliminating of the so-called back pressure within the conduit, to the end that lower steam pressures and reduced 80 quantities of steam will produce the same results, with a material saving in steam consumption. For the reasons pointed out, therefore, a device embodying the features of the invention is an advantageous adjunct to conveying systems of the steam jet type, the same having for its ultimate function 85 the securing of greater efficiency of operation and reduction of cost of maintenance of the entire ash conveying system.

I claim as my invention:

1. An ash conveying system, comprising 95 a conduit, means for introducing steam into said conduit, a relief pipe communicating at one end with said conduit adjacent the point of introduction of the steam and at its other end with the atmosphere, and an 100 enlarged drum located intermediate the ends of said relief pipe.

2. An ash conveying system, comprising a conduit, means for introducing steam into 105 said conduit, a relief pipe communicating with said conduit and with the atmosphere, the portion of said pipe adjacent the conduit being inclined rearwardly to the direction of flow of the steam, and an enlarged drum located intermediate the ends of said 110 pipe and adjacent said inclined portion thereof.

3. An ash conveying system, comprising a conduit, a nozzle in said conduit adapted 115 to inject steam therethrough, a relief pipe communicating with said conduit and with the atmosphere adjacent said nozzle and provided with a vertically arranged enlarged portion forming a chamber intermediate its ends, said chamber having a 120 downwardly tapered portion at its lower end.

4. An ash conveying system, comprising a conduit, a nozzle mounted in said conduit and adapted to inject steam longitudinally 125 thereof, a pipe connected with said conduit at a predetermined point beyond said nozzle in the direction of flow of the steam and inclined rearwardly toward said nozzle, said pipe communicating with the at- 130

mosphere and provided intermediate its ends with an enlarged drum, and a check-valve mounted at the discharge end of said pipe, and a counter-weight acting to effect the opening and closing of said valve with the changes in the air pressure in the pipe relative to atmospheric pressure.

In testimony that I claim the foregoing

as my invention, I affix my signature in the presence of two witnesses, this 1st day of 10 March, A. D. 1917.

ARTHUR P. STRONG.
